[57] CLAIM

The ornamental design for a M1A/M14 recoil buffer, as shown.

DESCRIPTION

FIG. 1 is an isometric view of the M1A/M14 recoil buffer showing the unique design of the invention;

FIG. 2 is an front view of the M1A/M14 recoil buffer, the back view being identical to the front view;

FIG. 3 is a side view showing one side of the M1A/M14 recoil buffer, the other side view being identical; and,

FIG. 4 is a bottom view of the M1A/M14 recoil buffer.
